UNITED STATES PATENT OFFICE.

ARTHUR B. CLUNIES, OF ROCHESTER, NEW YORK, ASSIGNOR TO THE SILL
STOVE WORKS, OF SAME PLACE.

DESIGN FOR A FIRE-POT LINING.

SPECIFICATION forming part of Design No. 25,889, dated August 4, 1896.

Application filed June 18, 1896. Serial No. 596,083. Term of patent 14 years.

To all whom it may concern:

Be it known that I, ARTHUR B. CLUNIES, a citizen of the United States, residing at Rochester, in the county of Monroe and State of New York, have invented and produced a new and original Design for Fire-Pot Lining-Sections, of which the following is a specification, reference being had to the accompanying drawings thereof.

Figure 1 is a perspective view of my design for a fire-pot lining-section, and Fig. 2 a plan view of the same.

The leading feature of my design is the shape and configuration of the lining-section adapted to be used in the fire-pots of stoves or ranges.

The top of the lining-section is indicated by 1 and the face by 2, the corner connecting them being curved, and the top 1 is recessed at 3 at one end and at the other a recess 4 is

formed. The end of the section beneath the recess 3 is narrowed, as shown by the full lines, or it could be continued down, as indicated in dotted lines, without altering, essentially, the appearance of the article. One end 25 of the face 2 of the article is curved slightly outward at 5 to meet the surface 6, at the upper end of which is the recess 4, and the lower edge of the article beneath the surface 5 is cut away at 7 and 8. The lower edge of the 30 article beneath the right end of the face 2 is cut away at 9 and 10 to form the recesses shown.

What I claim is—

The design for a fire-pot lining-section substantially as herein described and shown.

ARTHUR B. CLUNIES.
